GRINDING MACHINE

Hermon G. Weinland, Springfield, Ohio, assignor
to The Safety Grinding Wheel & Machine
Company, Springfield, Ohio, a corporation of
Ohio

Application July 28, 1932. Serial No. 625,256

14 Claims. (Cl. 51—122)

This invention relates to improvements in grinding machines, it more particularly relating to a machine of the type which has a reciprocating work table and a tool holder which is intermittently fed to the work.

One of the objects of the invention is to provide means controlled by the feeding movement of the tool holder for automatically changing the speed of the table after a predetermined movement of the tool holder.

Another object of the invention is to provide means controlled by the feeding movement of the tool holder for automatically causing the work table to move from working position to unloading position.

Another object of the invention is the provision of a fluid operated control mechanism controlled by the feeding movement of the tool holder for changing the speed of the work table after a predetermined movement of the tool holder; a further object in this connection being also to provide fluid operated mechanism controlled by the feeding movement of the tool holder to cause the work table to be placed in loading position after a further predetermined movement of the tool holder.

Other objects will appear from the accompanying description and statement of advantages.

In the accompanying drawings:

30 Fig. 1 is an end elevation of a grinding machine embodying the improvements.

Fig. 2 is a partial front elevation on a larger scale of the machine.

35 Fig. 3 is a fragmentary front elevation on a larger scale, partly in vertical section, of a portion of the tripping mechanism.

Fig. 4 is a partial transverse section, partly in elevation, on the line 4—4 of Fig. 3.

40 Fig. 5 is a view similar to Fig. 4 but with some of the parts shown in a different working position.

Fig. 6 is a fragmentary transverse section on the line 6—6 of Fig. 4.

Fig. 7 is a fragmentary transverse section on the line 7—7 of Fig. 4.

45 Fig. 8 is a fragmentary side elevation on a larger scale, partly in transverse section, of a portion of the fluid operated feeding mechanism, and includes a partial side elevation of one of the tool heads with the cover of the casing removed.

50 Fig. 9 is a view partly in horizontal section and partly in plan, the sectional portion being taken on the line 9—9 of Fig. 8.

Fig. 10 is a fragmentary transverse section partly in elevation on a slightly enlarged scale on the line 10—10 of Fig. 8.

Fig. 11 is a horizontal section on the line 11—11 of Fig. 10.

Fig. 12 is a diagrammatic view in perspective showing on a slightly increased scale as compared to Fig. 1 the relation and interconnection of the parts employed in the fluid operated controlling mechanism.

Fig. 13 is an elevation partly in longitudinal section of a detail used in connection with the control mechanism.

Fig. 14 is also an elevation, partly in longitudinal section, of a detail.

In the machine of this application the work table is given a reciprocatory movement by a rotary reversible fluid motor which is reversed by the contact of dogs on the work table with suitable tripping mechanism which controls a fluid operated reversing valve for the motor. The tool holder is advanced or fed toward the work in successive intermittent movements, a feeding movement occurring at each reversal of the work table, and the tool holder is retracted to an initial starting point by fluid operated means controlled by the work table when the work table reaches the unloading position. Provision is made for reciprocating the work table at a given speed to impart to the work a series of roughing cuts and thereafter automatically reciprocating the work table at a reduced speed to impart to the work a series of finishing cuts, this change in speed being under the control of the tool holder feeding mechanism. Provision is also made for automatically causing the work table to move to unloading position after a predetermined number of finishing cuts have been imparted to the work, this latter movement of the table being also under the control of the tool holder feeding mechanism.

Referring to the drawings, 1 represents a bed on the upper surface of which is slidably mounted a table or work holder 2 on a V-way 3 and a flat way 4. Motion is imparted to the work holder by a reversible rotary fluid motor 5 (Figs. 1 and 2), the fluid in the present case being compressed air, and the motor a rotary compressed air motor mounted at the rear and at the right end of the base 1. The motive power is transmitted to the work holder 2 through a train of gearing (Figure 2) there being a pinion 7 secured to the shaft 6 of the fluid motor 5 meshing with an idler gear 8, a pinion 9 secured thereto, a second idler gear 10 with which the idler pinion 9 meshes and a pinion 11 secured to the idler gear 10. The pinion 11 meshes with a master gear 12 which also is in mesh with a

rack 13 affixed to the under side of the work holder 2.

A grinding element is indicated at 14. This is a ring type wheel, the grinding operation being performed by applying the face of the ring to the work. The grinding wheel 14 is supported in a cup-shaped chuck 15 which is secured at the forward end of a spindle 16 rotatably mounted in a tool holder or head 17 slidably mounted on the upper surface of a lateral extension 18 of the base 1. An electric motor 19 is mounted on the tool head 17 and transmits its power to the spindle 16 by means of a plurality of V-belts 20 passing over a grooved pulley 21 on the motor shaft and over a grooved pulley 22 on the wheel spindle 16.

In the present machine the work holder movement is reversed by actuation of a pilot valve which controls a fluid motor, operating the reversible valve of the work holder rotary motor by contact of adjustably positioned pivotal stop dogs 24 and 25 secured on the forward vertical edge of the work holder cooperating with a pair of trip levers. One of the stop dogs, such as the dog 24 (Figs. 1 to 5 inclusive) makes contact with one lever 26 of a pair of trip levers 26 and 27, each of which is keyed by a key 27' (Fig. 7) to the reduced diameter outer extension of a short hollow horizontally disposed rock shaft 28. Each trip lever is placed side by side on the shaft 28, and the stop dog 25 is sufficiently offset with reference to the dog 24 so as to make contact only with the mating lever 27. Each trip lever is forced through a portion of its swing by the direct contact of the stop dog, while the remaining portion is accomplished by a well known camming device, a boss b on the trip lever 27 riding under the point of a resiliently supported wedge shaped block b'. This block acts as a cam to quickly complete the shift of the pilot valve and thereby eliminates the possibility of a failure of the work holder to reverse due to a stoppage of the piston valve at its mid-stroke. If there is any tendency of the work holder to overrun, the stop dog merely passes over the upper end of its respective trip lever. Therefore, when each dog in turn strikes its respective trip lever, the fluid motor 5 is reversed through mechanism now to be described and the direction of the work holder 2 is changed.

The rock shaft 28 which is hollow for a greater portion of its length, there being an axial bore 28' therein extending from its inner end to near its outer end, is rotatably supported in bosses 29 integrally attached to a cover plate 30 (Figs. 3 and 4) secured to the forward wall of the base 1. The rock shaft 28 projects into the interior of the base 1, and on the inner end thereof is clamped a member 32 having a downwardly extending crank arm 33, the angular position of which thereof with respect to the trip levers may be readily altered, if desired, by loosening the member clamping bolt 35, with which the member 32 is provided.

Work-holder motor reversing devices

Instead of mechanically connecting the trip levers with the reversing valve of the fluid motor 5, fluid pressure devices are employed, similar to the fluid operated means shown in my co-pending U. S. application Serial No. 577,903. The motor reversing valve 36' is housed in an extension 36 (Fig. 1) of the motor 5, and is provided with a downwardly extending lever 37 (Figs. 1 and 2). The reversing valve is rocked

to and fro by a fluid motor having a cylinder 38, a piston 39 (Fig. 2) and a piston rod 40, the piston rod being connected at its outer end by links 41 to the lower end of the reversing valve lever 37.

Fluid is supplied alternately to each end of the reversing motor cylinder 38 through conduits 42 and 43 (Figs. 1, 2 and 12) from a pilot valve cylinder 44 under control of a pilot valve 45, which in turn is reciprocated through direct mechanical connections by the work holder movements. The pilot valve 45 is provided with a piston rod 46 (Figs. 3 and 12), the outer end of which is pivotally connected by a link 47 to the lower end of the crank arm 33. With a movement of the work holder 2 to the left, the dog 25 strikes the trip lever 27 which is then in a vertical position as shown by the dot dash lines (Fig. 3) and swings it to the left or to the full line position, which movement results in shifting the pilot valve to the opposite end of its travel.

The pilot valve 45, as shown in full lines in Fig. 3, by diverting the fluid received through the supply conduit 48 (Figs. 3 and 12) to the conduit 42 by means of the circumferential centrally located groove 49 of the pilot valve 45, is in position to supply fluid to the left end of the reversing cylinder 38 through the conduit 42. The movement of the piston 39 to the right rocks the reversing valve to a position by which the motor 5 is caused to run in a direction whereby the work holder will be moved to the left. During this movement of the pilot valve, fluid displaced from the right end of the cylinder 38 is permitted to escape to atmosphere through the conduit 43 and through an exhaust port 50.

When the pilot valve 45 is forced to the right as shown by the broken line in Fig. 3 by contact of the stop dog 25 and the trip lever 27, the fluid received through the supply conduit 48 is cut off from the conduit 42 and is diverted to the conduit 43 leading to the right end of the reversing cylinder 38, forcing the piston 39 therein to the left, thereby reversing the direction of the work holder. The fluid displaced from the left end of the cylinder 38 flows through the conduit 42 and escapes to atmosphere through a plurality of ports 51 in the pilot valve 45 and through the port 50 as described above.

The trip lever 26 is slidably mounted on the rock shaft 28, the key 27' serving as a spline, whereby the trip lever may be moved from its normal position for a purpose which will appear later. The normal position of the trip lever 26 is such that it will be struck by the stop dog 24 and is retained in normal position by the pressure of a coiled spring 52, one end of which bears against the hub 53 (Figs. 4 and 5) of the lever 26, the other end bearing against a disk 54 secured at the outer extended end of the rock shaft 28, there being a flat head screw 56 threaded into the solid end of the rock shaft 28 for this purpose.

Tool-head positioning and feeding

The tool head 17 is preliminarily positioned a predetermined distance from the work by manual rotation of a lead screw 57 (Figs. 8 and 8), as for example, so that the face of the wheel is one-eighth inch therefrom, in order to allow a piece of work in the rough to pass the wheel. At each reversal of the work holder, the tool head 17 is fed towards the work a predetermined distance by a fluid operated feeding mechanism also similar in principle to the feeding mechanism

shown and described in my co-pending U. S. application Serial No. 577,903, and again described in detail herein in order to explain the action of additional fluid controlling devices employed in conjunction with the tool holder feeding devices mentioned whereby the work holder speed of movement is reduced at the conclusion of the roughing cuts, and further at the completion of the finishing cuts the work holder is returned to the loading position.

The mechanism by which the intermittent feeding is accomplished is housed in a casing 58 secured to the side of the tool head 17. A ratchet disk 59 is rotatably mounted on a horizontally disposed stud 60 projecting forwardly from the rear wall of the casing 58, and which is provided with an axial bore 60' (Fig. 9) for the greater portion of its extended length.

The ratchet disk is intermittently actuated to cause successive partial rotation in one direction by the engagement of a pair of spring-pressed pawls, 61 and 62, (Fig. 8) one each being positioned in the outer end of each of a pair of diametrically opposed levers 63 and 64 (Figs. 8 and 9), the pawl 61 being so turned that a downward movement of the lever 63 engages the ratchet teeth and results in a partial rotation in an anti-clockwise direction, while the pawl 62 is so placed in the lever 64 that an upward movement of the lever 64 continues the anti-clockwise partial rotation of the ratchet disk 59. The lever 63 is pivotally mounted on a stud 65, and its mating lever 64 is also pivotally mounted on a stud 66. Both the studs 65 and 66 are fixed in a member 67 secured in the present case by a cross-pin to the outer end of the hollow stud 60. Each lever 63 and 64 is interconnected at its adjacent end by a link 68 so that motion from one causes a similar movement in the other.

The levers 63 and 64 are alternately moved upwardly and downwardly by means of a small fluid motor, the cylinder of which is represented at 69. In the cylinder 69 is fitted a piston 70 having a piston rod 71 attached thereto. The upper end of the piston rod is pivotally connected to the lever 63, and the cylinder 69 is pivotally supported at its lower end to the inside lower portion of the casing 58 to allow for the arcuate movement of the cylinder due to the direct connection of the piston with the lever 63. At each reversal of the work holder 2, fluid pressure is delivered at each end alternately of the cylinder 69 through conduits 72 and 73 (Figs. 2, 3 and 12) from the cylinder 44 under the control of the pilot valve 45, and through means to be described the tool head 17 is moved intermittently towards the work.

The distance the tool head moves at each reversal is governed by varying the distance through which the levers 63 and 64 swing, from a full swing, where several ratchet teeth are engaged and a movement of several one-thousandth parts of an inch results, to a swing where one tooth only is engaged and the minimum movement of the tool head of .001 inch is made.

The means for limiting the swing of the levers consists in the present instance, of a pair of jaw members, one jaw 74 being interiorly threaded with a right-hand thread while the jaw 74' is provided with a left-hand thread (Fig. 8). Both jaws are threaded on a vertically disposed threaded rod 75 rotatably supported in bearings integrally attached to the member 67 and each jaw projects outwardly so that the upper jaw 74 extends over, and the lower jaw 74' extends be-

low the lever 63. Thus with rotation of the threaded rod 75 in one direction the jaws are moved toward each other and thereby shorten the allowable swing of the lever to the space between the jaws to impart a relatively small movement of the tool head, and if the jaws are spread apart by rotating the rod 75 in the other direction, the possible swing and tooth engagement is increased, and the amount of feed per reversal is increased.

In the present machine, the fluid operated tool feeding devices employ a segment arm, a pinion and a rack in the same manner as described in the aforementioned co-pending application Serial No. 577,903. The segment arm 76 is keyed to a horizontal shaft 77 (Figs. 8 and 9) carried in bearings 78, one of which is indicated in Fig. 9. Near the center, the shaft 77 is provided with a pinion 79 which meshes with a short rack 80. The teeth of the rack 80 are milled in an integral extension of a nut 81 through which the lead screw 57 is threaded. The nut 81 is slidably mounted on the under side of the tool head 17 and retained in position by gib 82 (Fig. 8) secured to the tool head. Therefore, when the segment arm 76 is moved in either direction the resulting rotation of the pinion 79 causes the tool head 17 to be moved either toward or from the work, as the case may be, since the rack 80 being connected to the nut 81 is at the time stationary positioned, the lead screw 57 being journaled in bearings in the bed extension 18.

The train of gearing mentioned as being employed in connection with the tool feeding mechanism is for the purpose of permitting the use of a small fluid motor to actuate the levers 63 and 64, as, with the small motor, forward motion of the tool head may be arrested at any desired point by allowing the segment arm 76 to come into contact with a suitably adjusted stop, and the small motor is "stalled" with no damage or change in position of the tool head, or interruption to other operations.

In the circular periphery of the segment arm 76 gear teeth are cut, with which the teeth of a pinion 83 are meshed. The pinion 83 is secured to a gear 84 which is rotatably mounted on a stud 85 secured to the rear wall of the casing 58. A freely rotatable pinion 86 carried on the hollow stud 60 meshes with the gear 84, and receives its motion from the ratchet disk 59 through a frictional arrangement consisting of a fiber plate 87 interposed between the disks 88 and 89 integrally attached respectively to the rear side of the ratchet disk 59 and the pinion 86. Pressure is maintained on the fiber plate 87 by means of a coiled spring 90 (Fig. 9) to provide sufficient friction to drive the parts, the spring being placed in a counter bore in the hub of the ratchet disk 59 and encircling the hollow stud 60 at that point, and bearing against the member 67. The purpose of the frictional arrangement will appear later.

Work-holder speed change

It has been stated that the grinding operations consist of roughing and finishing grinding cuts, the roughing cuts being taken at a certain work holder speed while the finishing cuts are performed at a lower rate. Provision by which the work holder speed is altered automatically, allowing by adjustment a predetermined number of roughing cuts to be made, followed by a predetermined number of finishing cuts at the lower speed will now be explained.

During the rough grinding operations, the segment arm 76 descends intermittently, and in the path of this arm is the free end of a lever 91 (Fig. 10) pivotally connected at its other end to one end of a valve casing 93, which lever when depressed by the segment arm opens successively two valves. The first of these valves to open is shown at 92 (Figs. 10 and 11). This valve is caused to be opened when sufficient roughing cuts have been made and the work holder speed is to be reduced for the remaining strokes thereof. This is accomplished by providing that by suitable adjustment the valve 92 may be made to open at an earlier or later period with reference to the time of contact of the segment arm 76 with the lever 91, there being an adjusting screw 94 threaded into and so located in the lever 91 as to bear against the upper end of the stem 92' of the valve 92.

When the valve 92 opens, fluid is passed from the supply conduit 96 (Figs. 8, 11 and 12) to a conduit 97 leading from the casing 93 to the cylinder 98 (Fig. 13) of a fluid-operated throttle valve interposed in the main supply conduit 99 leading to the rotary motor 5 (Figs. 1, 2 and 12) whereby a piston 100 (Fig. 13) in the throttle valve cylinder is forced downwardly. The piston 100 has a piston rod 101, at whose lower end is fixed a valve 102 of the poppet type, and the downward movement of the piston 100 causes the valve 102 to be seated on its seat in the valve body 103. The disk portion of the valve 102, however, is provided with a plurality of openings, the size and number of which insure that sufficient fluid is passed therethrough to operate the work holder at the desired lower speed.

Work holder return to loading position

For each subsequent reversal of the work holder the segment arm 76 further depresses the lever 91. This further movement eventually opens the second valve 105 similarly housed in the casing 93, the valve 105 being actuated by contact of an adjustable screw 106 threaded in the lever 91, being brought to bear against the upper end of the stem 105' of the valve 105. The screw 106 is adjusted to provide a clearance space 108 (Fig. 10) between the contacting ends of the valve stem and screw thereby allowing a certain number of finishing cuts to be made.

When the valve 105 is opened, fluid pressure is allowed to flow from the supply conduit 96 through a short port 109, and after passing the valve 105 through a conduit 110 (Figs. 9 and 12) to the interior of the rock shaft 28 (Figs. 4 and 5) previously mentioned. It was previously stated that the trip lever 27 is rigidly attached to the rock shaft 28, while the trip lever 26 is slidably supported thereon but keyed therewith by a spline, and that this trip lever 26 is retained in its normal position by a coiled spring 52. The fluid impulse received from the valve 105 causes the trip lever 26 to be moved outwardly against the compression of the spring 52, for the purpose of allowing the stop dog 24 to pass by the trip lever 26 on a movement of the work holder to the right and to continue in that direction to the loading position where the finished work is removed.

This is accomplished by fitting a small piston 111 in the bore of the rock shaft 28. Upon admission of fluid pressure to the bore of the shaft 28, the piston 111 moves outwardly and bears against a cross-pin 112, which is loosely fitted through axial slotted openings 113 (Figs. 4, 5 and 6) in the rock shaft 28. The projecting ends of the cross pin 112 bear against the recessed hub 114 of the

trip lever 26, the cross pin being retained by the circumferential wall 115 obtained in forming the recess 114. The inner end of the rock shaft 28 is closed with a threaded plug 116 (Fig. 5) having a port 117 whereby fluid from the conduit 110 is conducted to the interior of the shaft 28.

Referring to Fig. 4 in which the normal position of the trip lever 26 is shown, it will be seen that the dog 24 will strike the trip lever 26 and cause a reversal of the work holder as described. In Fig. 5, however, the trip lever 26 is shown as having been moved out of the path of the dog 24, and therefore no contact resulting in reversal is made and the work holder continues to move to the right.

The continued movement of the work holder 2 to the right when the trip lever 26 is thrown out of contacting position is arrested at the right end of the bed 1, at the loading position, by the contact of the stop dog 24 with a trip lever 118, which when swung to the dot dash position as seen in Fig. 3, causes the closing, through linkage to be described, of a dual purpose valve 119 enclosed in a valve body 120 (Figs. 1, 2, 12 and 14). This valve 119 is interposed in the main fluid supply conduit 99 and the conduit 99' leading to the rotary fluid motor 5, and when closed, the fluid to the motor 5 is shut off and the work holder 2 comes to a stop.

The valve 119 is actuated through linkage as follows: The trip lever 118 is attached to a shaft 121 which is rotatably mounted in a boss 123 (Fig. 3) in the forward side of the base 1. On the inner end of the shaft 121, a crank arm 124 is secured at whose lower end is pivotally connected a link 125, the opposite end of which is pivotally connected to the upper end of a lever 126 secured to the stem of the valve 119 (Fig. 14). The shaft 121 has also attached thereto a hand lever 127, which moves to the depressed position shown in broken lines when the valve 119 is closed. As the motor 5 was stopped when running in a direction whereby the work holder moves to the loading position at the right, provision is made to change the reversing valve so the work holder can move only to the left when the valve 119 is again opened, and to also place the trip lever 27 in operative position. This is accomplished by linking the rock shaft 28 with the trip lever 118. A rod 128 (Fig. 3) is pivotally connected at one end to the inner side of the trip lever 26. The other end of the rod is passed loosely through a cross-wise opening in a swivel block 129 loosely and rotatively mounted on the inner side of the trip 118. Near the free end 128' of the rod 128 is adjustably fixed by a set screw, 130 a collar 130 at such distance from the swivel block 129 as to cause no interference with the ordinary swinging movements of the trip levers 26 and 27 when the trip lever 118 is in vertical position, in which position the valve 119 will be open. The collar is, however, sufficiently close to the block 129 as to insure that, when the valve 119 is closed either manually by depression of the handle 127, or by contact of the stop dog 24 with the trip lever 118, the trip lever 27 will assume its vertical position as shown in dot dash lines in Fig. 3.

As before stated, this movement of the trip levers results in a shift of the pilot valve 45 with the further result that the reversing valve of the work holder rotary motor 5 is also shifted. The motor 5 can then start, when fluid is again admitted to it by raising the hand lever 127, only in the direction whereby the work holder is moved from the loading position and is thus prevented

from running off the right hand end of the bed. Further, the trip lever 27 is also brought into position to limit and reverse the movement of the work holder to the left.

5 *Retraction of tool head*

The closure of the valve 119 also accomplishes purposes other than stopping the work holder, in that the tool head 17 is retracted to its initial point and incidentally portions of the feeding mechanism are restored to the starting position. The fluid pressure on the trip lever 26 is also relieved whereby the spring 52 returns the trip lever 26 to its normal position. Full speed operation of the work holder is also resumed when the valve 119 is again opened.

Referring to Fig. 14 the valve 119 is shown in its open position, the curved port 131 therein being in communication with the conduits 99 and 99'. To shut off the fluid to the motor 5 the valve 119 is rotated in an anti-clockwise direction, the port 131 assuming the broken line position. This position provides that a small amount of fluid is admitted to a conduit 132 through a small port 133 in the body 120. The conduit 132 branches into the conduits 134 and 135, the conduit 134 leading to a fluid motor formed in the hollow shaft 60, and the conduit 135' to a fluid motor 135 connected with the segment arm 76, both of which are parts of the feeding mechanism. When the valve 119 is returned to the open position shown in full line position in Fig. 14, the said motors are connected to atmosphere through a small port 153, a flattened side 119' of the valve 119 connecting the conduit 132 with the port 153.

The fluid motor 135 is employed to force upwardly the segment arm 76 and thereby retract the tool head 117, and consists of a cylinder 136 (Fig. 8) pivotally connected to the inner bottom wall of the casing 58, a piston 137 and a piston rod 138, the piston rod 138 being pivotally connected to the segment arm near the upper central portion thereof, and fluid pressure is admitted to the cylinder 136 below the piston. Before the upward movement of the segment can take place, however, since the pawls 61 and 62 are at all times in engagement with the teeth of the ratchet disk 59, it is necessary that the ratchet disk 59 be freed from its frictional engagement with the pinion 86, whereby the pinion 86 is allowed to rotate freely. The release of the frictional engagement is made as follows: In the hollow shaft 60 a piston 139 is fitted. This piston bears against a cross pin 140 positioned in a manner similar to that described in connection with the trip lever 26. The cross pin 140 is loosely inserted in elongated openings in the walls of the shaft 60, and its projecting ends bear against the recessed hub of the ratchet disk 59. The movement is limited to but a few thousandth parts of an inch, being merely sufficient to relieve the friction of the plate with the adjacent members. Thus when an application of fluid pressure is made simultaneously the frictional engagement is broken, and the segment arm 76 is forced upwardly. As the arm 76 rises, the lever 91 follows it for a short distance in its upward movement and the valves 92 and 105 are seated due to the combined pressure of a plurality of coiled springs, there being a spring 149 below the valve 92, and a spring 150 below the valve 105. The seating of this valve 92 results in allowing the speed reducing valve 102 to rise and provide the full area fluid flow where-

by the higher work holder speed is obtainable on again starting the machine.

The fluid displaced by the rise of the piston 100 is forced back through the conduit 97 into the bore 143 above the valve 92 and expelled to atmosphere by a ball-check valve 144 (Figs. 10 and 11), there being a port 145 leading from the bore 143 above the seat of the valve 92 to the chamber 146 in which the ball 144 is seated. The ball is lightly held to its seat by a spring 147 and a plunger 148, the spring 147 being interposed between the upper end of the plunger and the lower side of a laterally extending ear 148' on the lever 91.

The seating of the valve 105 by the rise of the segment arm 76 results in shutting off the fluid by which pressure is exerted against the piston 111 (Figs. 4 and 5) whereby the spring 52 now returns the trip lever 26 to its normal position. The expulsion of fluid from this motor is in a manner similar to that described for the speed reducing motor, the fluid being forced to return through the conduit 110 to the bore 151 above the seat of the valve 105, and thence to atmosphere, lifting a ball-check valve 151' (Fig. 11), there also being a port 151'' leading from the bore 151 to the chamber in which the ball 151' is seated. The ball 151' is also lightly held to its seat in the same manner as just described for the ball 144 and since the lever 91 normally rests on the springs by which the balls are held down, the downward movement of the lever 91 increases the pressure on the balls and provides sufficient additional loading to prevent escape of fluid when the valves 92 and 105 are opened.

The upward movement of the segment arm 76 which causes the tool head 17 to recede to its initially set position is arrested by contact of the arm with an adjustable stop screw 152 located in the sloping upper wall of the casing 58. Therefore, from the moment the segment arm 76 leaves the adjustable stop screw 152 to the time the arm depresses the lever 91 sufficiently to open the valve 105, the tool head 17 is advanced toward the work in successively intermittent movements occurring at each reversal of the work holder, while the receding movement of the tool head is made in one single movement. The swing is varied by turning the stop screw in or out, resulting in a total head movement of a lesser or greater degree, as desired.

125

Operation of machine

In operation, the work is placed on the work holder when this member is at its loading position, i. e., at the right hand end of the bed 1. To start the work holder, the hand lever 127 (Figs. 2 and 3) is swung upwardly to its horizontal position as shown in full lines. Through the linkage described, this movement results in placing the valve 119 (Fig. 14) in position to supply fluid to the rotary motor 5, and the friction releasing fluid motor in the shaft 60 and the segment arm motor 135 are permitted to exhaust to atmosphere. Inasmuch as the trip lever 26 had already returned to its normal position, work holder reversals will again be resumed automatically by the contact of the stop dogs 24 and 25 with the trip levers 26 and 27, respectively. After the desired number of roughing strokes have been made, the valve 92 is opened, resulting in a decrease in the work holder speed to provide a slower speed for the finishing cuts, at the conclusion of which the valve 105 is opened. The opening of the valve 105 results in forcing the trip lever 26 outwardly from its normal position, and allows the

140

145

150

work holder to move to the right to its loading position where the work holder is automatically stopped by closing the valve 119, and the work is removed. The closing movement of the valve 119 results in restoring the tool head to its initial position and incidentally allowing the speed reducing throttle to resume its fully opened position and to permit the trip lever 26 to again assume its normal position.

10 Manual manipulation of the lead screw 57 is resorted to to compensate for wheel wear and also to initially position the tool head 17. When the tool head is initially positioned, the distance the tool head will move forward depends on the movement allowed for the segment arm, and this movement is preferably held to the minimum, allowing the grinding wheel to merely clear the rough surface of the work and still advance to the point at which the work is finished. If more of 20 the surface is to be removed, the tool head 17 may be moved toward the work by use of the lead screw, but it would likely be advisable to run the stop screw 152 outwardly in order to provide a greater movement whereby the rough surface 25 may again be cleared.

Having thus described my invention, I claim:

1. In a grinding machine, a work table, means for reciprocating the table, a tool holder, means to impart a feeding movement to said holder, and means controlled by the feeding movement of said holder to change the speed of said table after a predetermined movement of said holder.

2. In a grinding machine, a work table, a motor for moving said table, means controlled by the table to reverse the direction of said motor to impart reciprocatory motion to said table, a tool holder, means for feeding said holder, and means controlled by the feeding movement of said holder to change the speed of said motor after a predetermined movement of said holder.

3. In a grinding machine, a work table, a fluid motor for reciprocating the same, a valve to control the speed of said motor, a tool holder, means to impart a feeding movement to said holder, and means controlled by the feeding movement of said holder to operate said valve to change the speed of said table after a predetermined movement of said holder.

4. In a grinding machine, a work table, a fluid motor for reciprocating said table, a fluid operated valve to control the speed of said motor, a control valve to control the fluid which operates the fluid operated valve, a tool holder, means to impart a feeding movement to said holder, and means controlled by the feeding movement of said holder for operating said control valve to admit fluid to said fluid operated valve to change the speed of said table after a predetermined movement of said holder.

60 5. In a grinding machine, a work table, a fluid motor for reciprocating said table, a normally open valve to supply fluid to said motor, said valve having a reduced fluid admission port therethrough, a control valve to control the fluid which operates said first valve, a tool holder, means for imparting a feeding movement to said holder, and means controlled by the feeding movement of said holder to operate said control valve to admit fluid to operate said first mentioned valve to close the same to thereby admit a reduced supply of fluid to said motor to reduce the speed thereof.

65 6. In a grinding machine, a work table, a fluid motor, means operated by the table to reverse the direction of said motor, a tool holder, feeding

devices to impart a feeding movement to said holder, and means controlled by the feeding devices for said holder to change the speed of said table after a predetermined movement of said holder.

70 7. In a grinding machine, a work table, a fluid motor, means operated by the table to reverse the direction of said motor, a tool holder, feeding devices to impart a feeding movement to said holder, and means controlled by the feeding devices for said holder to change the speed of said table after a predetermined movement of said holder, said means comprising a fluid operated valve to control the admission of fluid to said motor.

75 8. In a grinding machine, a work table, a fluid motor, means operated by the table to reverse the direction of said motor, a tool holder, feeding devices to impart a feeding movement to said holder, means controlled by the feeding devices for said holder to change the speed of said table after a predetermined movement of said holder, said means comprising a fluid operated valve to control the admission of fluid to said motor and a second valve operated by said feeding devices 90 to control the fluid which operates said first valve.

95 9. In a grinding machine, a work table, a fluid motor for reciprocating said work table, means including a pair of trips to reverse the motor at the end of each reciprocatory movement of said table, a tool holder, means for feeding said holder, fluid operated means for throwing one of said trips out of operative position to permit the motor to move the table to loading position, a valve controlling said fluid operated means, means for operating said valve by the feeding movement of said tool holder, a third trip to control the admission of fluid to said motor, and means on the table to operate said third trip to cut off the fluid to said motor when the table has 100 reached loading position.

105 10. In a grinding machine, a work table, means for reciprocating the table, a tool holder, means to impart a feeding movement to said holder, means controlled by the feeding movement of the holder to change the speed of said table after a predetermined movement of said holder, and means operated by the feeding movement of said holder to render the motor reversing means inoperative after a predetermined movement of 110 said holder to permit the table to be moved to loading position.

11. In a grinding machine, a work table, a motor for moving said table, means controlled by the table to reverse the direction of said motor 120 to impart reciprocatory motion to said table, a tool holder, means for feeding said holder, means controlled by the feeding movement of said holder to change the speed of said motor after a predetermined movement of said holder, and means operated by the feeding movement of said holder to render the motor reversing means inoperative after a predetermined movement of 125 said holder to permit the table to be moved to loading position.

130 11. In a grinding machine, a work table, a motor for moving said table, means controlled by the table to reverse the direction of said motor to impart reciprocatory motion to said table, a tool holder, means for feeding said holder, means controlled by the feeding movement of said holder to change the speed of said motor after a predetermined movement of said holder, and means operated by the feeding movement of said holder to render the motor reversing means inoperative after a predetermined movement of 135 said holder to permit the table to be moved to loading position.

140 12. In a grinding machine, a work table, a motor for moving said table, means controlled by the table to reverse the direction of said motor to impart reciprocatory motion to said table, a tool holder, means for feeding said holder, means controlled by the feeding movement of said holder to change the speed of said motor after a predetermined movement of said holder, means operated by the feeding movement of said holder to render the motor reversing means inoperative 145

after a predetermined movement of said holder to permit the table to be moved to loading position, and means operated by the table to cut off the supply of fluid to said motor when the table 5 has reached loading position.

13. In a grinding machine, a work table, a fluid motor for reciprocating said table, means operated by the table for reversing the direction of said motor at the end of each reciprocatory 10 movement of said table, a fluid operated valve to control the speed of said motor, a control valve to control the fluid which operates the fluid operated valve, a tool holder, means to impart a feeding movement to said holder, means controlled by the feeding movement of said holder

for operating said control valve to admit fluid to said fluid operated valve to change the speed of said table after a predetermined movement of said holder, and a second control valve operated by the feeding movement of said holder to render the motor reversing means inoperative to permit the motor to move the table to loading position. 80

14. In a grinding machine, a reciprocatory work table, a tool holder, feeding mechanism for said tool holder, said mechanism including pawls and an axially movable ratchet wheel, a gear normally engaged with said wheel, a fluid motor to move said wheel axially, and fluid supply means for said motor controlled by said work table. 85
